AMBULATORY STRETCHER

Lester L. Bauer, Toledo, Ohio, assignor to Gendron Wheel Company, Perrysburg, Ohio, a corporation of Ohio

Application January 12, 1955, Serial No. 33,931

Term of patent 3½ years.

(Cl. D83—1)

FIG. 1

I claim:

The ornamental design for an ambulatory stretcher,
as shown.
